W. CURLETT.

KEY FASTENER.

APPLICATION FILED AUG. 27, 1908.

927,835.

FIG. 1.

Patented July 13, 1909.

Fig. 2.

FIG. 5.

Fig. 6

A diagram of a circular disk with a central hole. The disk is labeled with the letter *g* at the top. In the center, there is a smaller circle labeled d^2 above it and c^2 below it. A vertical line labeled *h* extends from the center to the bottom of the disk. At the top of the disk, there is a vertical line labeled *F* and a horizontal line labeled *J* extending from the vertical line.

UNITED STATES PATENT OFFICE.

WILLIAM CURLETT, OF SAN FRANCISCO, CALIFORNIA.

KEY-FASTENER.

No. 927,835.

Specification of Letters Patent. Patented July 13, 1909.

Application filed August 27, 1908. Serial No. 450,538.

To all whom it may concern:

Be it known that I, WILLIAM CURLETT, citizen of the United States, residing at San Francisco, in the county of San Francisco 5 and State of California, have invented new and useful Improvements in Key-Fasteners, of which the following is a specification.

My invention pertains to locks, and more particularly to means for fastening keys 10 therein; and its novelty, utility and practical advantages will be fully understood from the following description and claim when the same are read in connection with the drawings, accompanying and forming 15 part of this specification, in which—

Figure 1 is a sectional view illustrating a lock equipped with my improvements, and also illustrating a key properly arranged relative to the lock and the improvements. Fig. 20 2 is an elevation showing the escutcheon and the gravitating bolt comprised in my improvements. Fig. 3 is a diagrammatic view illustrating the relative arrangement of the disk and the gravitating bolt comprised in 25 my improvements when the keyhole in the disk is in registration with that in the escutcheon. Fig. 4 is a view like Fig. 3, but showing the disk and the gravitating bolt in different positions. Fig. 5 is a detail view, 30 partly in elevation and partly in section, showing a modified disk and key constructed in accordance with my invention. Fig. 6 is an edge elevation of the modified disk.

Similar letters designate corresponding 35 parts in all of the views of the drawings, referring to which:

A is a door equipped with a lock B of the conventional construction or of any other construction consonant with the purpose of 40 my invention.

C is the key complementary to the lock, which key is preferably of the ordinary construction, with the exception that it is provided on its shank a with a radial projec- 45 tion b.

D is an escutcheon fixed on the inner face 50 of the door and having a keyhole c alined with that of the lock and a notch d extending upwardly from the upper end of the keyhole c and also having a vertical slot e arranged above and in line with the keyhole c.

E is the disk of my improvements, and F is the gravitating bolt for coöoperating with the disk E in the manner hereinafter set forth 55 in detail.

Suitably attached to the inner side of the

escutcheon D is a flange f of angular form in cross-section, and in the said flange and between the same and the adjacent side of the escutcheon D the disk E is retained in such 60 manner that it is adapted to rotate or turn through a part of a revolution with the before mentioned key C. As best shown in Figs. 3 and 4, the disk E is provided with a keyhole c² and a notch d² similar to the corresponding features of the escutcheon D, and said disk is also provided with a notch g of V-shape, and a notch h of U-shape; both of the said notches being formed in the periphery of the disk and about the proportional distance illustrated apart.

As best shown in Fig. 1, the gravitating bolt F is disposed with its major portion at the inner side of the escutcheon D, and is provided with a depending portion i, disposed at the inner side of the flange f, and is also provided with a rectangular portion j arranged and movable vertically in the slot e of the escutcheon, and carrying a threaded shank k for the connection of a knob or finger-piece l.

It will be readily understood from the foregoing that when the key C is placed in the lock from the inside of the door, the projection b on the shank of the key will assume a 85 position inside of the escutcheon D and in the notch d² of the disk E. At this time the gravitating bolt F rests in the notch g of the disk E, the purpose of said engagement being to prevent casual movement of the disk E 90 from its normal position, in which position its keyhole c² is coincident with the keyhole of the lock. When the key is turned to shoot the bolt of the lock, the projection b on the key shank will turn the disk E with the 95 key so as to carry the keyhole of the disk out of registration with the keyhole in the escutcheon, and at the same time carry the notch h to a position under the bolt F, whereupon the said bolt F will seat in said notch h 100 and by so doing will lock the disk E in a position to guard and seal the keyhole in the escutcheon D. From this it follows that the disk E is adapted when locked to prevent 105 displacement of the key and picking of the lock, and is also adapted to effectually close the keyhole c in the escutcheon which is advantageous for obvious reasons. It also follows that when a person at the inside of the door is desirous of opening the door, it is 110 simply necessary for such person to first raise the bolt F and then turn the key C, since

when this is done the disk E will be turned until its notch g is presented to the bolt F, at which time the drop of the bolt and the retardation of the disk E will apprise the person of the fact that the keyholes c c^2 are in registration and that consequently the key may be withdrawn from the door if desired.

The modified key C' of Fig. 5, differs from the key shown in Fig. 1 in that its projection b' extends laterally inward from its shank. The modified disk E of Figs. 5 and 6 has a keyhole c^3 to receive the key C' and also has projections c^5 at opposite sides which render it reversible and adapt it to turn freely at the inner side of the escutcheon. In this connection it will be noted that the illustrated arrangement of the projection b' on the shank of the key C' renders it unnecessary to provide the disk E' with a notch d^2 such as shown in Figs. 3 and 4.

It will be gathered from the foregoing that all of the parts of my improvements are carried by the escutcheon D; also, that the construction as a whole is simple and inexpensive and at the same time is reliable in operation, this latter being largely due to the fact that the specific arrangement of the bolt F and the finger-piece l, relative to the other parts, assures free vertical movement of the bolt.

Having described my invention, what I claim and desire to secure by Letters-Patent, is:

The key fastener described comprising an escutcheon having a keyhole and a vertical slot disposed above the keyhole and also having a flange f at its inner side, a rotatable disk retained in said flange and between the same and the inner side of the escutcheon and having a keyhole and also having spaced notches in its periphery, one of which is comparatively shallow, a gravitating bolt movable above the disk and into and out of the notches thereof and arranged at the inner side of the escutcheon and having a depending portion i disposed at the inner side of the flange f and also having a rectangular portion j arranged and movable vertically in the slot of the escutcheon, and a finger-piece connected with said portion j of the bolt and arranged against the outer side of the escutcheon.

In testimony whereof I have hereunto set my hand in presence of two subscribing witnesses.

WILLIAM CURLETT.
